(57) CLAIM

The ornamental design for a carrying case with speakers for tablet computers, as shown and described.

DESCRIPTION

FIG. 1 is a perspective view of the carrying case with two speakers;

FIG. 2 is a top view of the carrying case of FIG. 1;

FIG. 3 is a bottom view of the carrying case;

FIG. 4 is an end view of the carrying case;

FIG. 5 is an opposing end view of the carrying case;

FIG. 6 is a side view of the carrying case;

FIG. 7 is an opposing side view of the carrying case;

FIG. 8 is perspective view of an alternative embodiment of the carrying case, the only difference being the number of speakers attached to the case;

FIG. 9 is perspective view of an alternative embodiment of the carrying case, the only difference being the number of speakers attached to the case;

FIG. 10 is an end view of the carrying case of FIG. 9; and,

FIG. 11 is an opposing end view of the carrying case of FIG. 9.
